Primary Examiner — Karen E Kearney*Assistant Examiner* — John M Otte(74) *Attorney, Agent, or Firm* — Finnegan, Henderson, Farabow, Garret & Dunner LLP(57) **CLAIM**

The ornamental design for a display screen with graphical user interface, as shown and described.

DESCRIPTION

The FIGURE is a front view of a display screen with graphical user interface showing the new design.

The broken lines of uneven length show the display screen and form no part of the claim. The broken lines of even length illustrate portions of the display screen with graphical user interface and form no part of the claimed design.

1 Claim, 1 Drawing Sheet(56)
